US00D909291S

(12) **United States Design Patent** (10) Patent No.: **US D909,291 S**
(45) Date of Patent: **** Feb. 2, 2021**

(54) **BATTERY**

- (71) Applicant: **Zebra Technologies Corporation**,
Lincolnshire, IL (US)
- (72) Inventors: **James Lucas**, Coventry, RI (US);
Anthony Ross Helberg, Attleboro, MA
(US); **Robert Hutnak**, Douglas, MA
(US); **Yun Hua**, Broadview Heights,
OH (US)
- (73) Assignee: **Zebra Technologies Corporation**,
Lincolnshire, IL (US)

(**) Term: **15 Years**

(21) Appl. No.: **29/673,832**

(22) Filed: **Dec. 18, 2018**

(51) LOC (13) Cl. **13-02**
(52) U.S. Cl.
USPC **D13/103**
